MOVING SCREEN FOR OIL BURNERS

Moritz Gaertner, New York, N. Y.

Application January 23, 1943, Serial No. 473,296

9 Claims. (Cl. 158—1)

This invention relates generally to furnaces such as used in industrial establishments, buildings, and the like. More particularly, my present invention relates to control means for more efficient heat production in combustion chambers, its more thorough absorption and delivery, and especially its distribution at more unified temperatures through different parts of such chambers. Such heat control means are also provided that may be installed in and used with otherwise standard furnaces.

During or at the initiation of combustion in the chambers of oil furnaces, a considerable volume of air, steam or compressed gas is introduced for producing a proper mixture. The spray cone has heretofore been constantly deflected by the resultant exploding gases. This caused a whirl of very hot gases and air, and great spaces of cold air and partly gasified oil fumes. The heat reflected from the walls of the combustion chamber is in most cases too far away for a complete gasification, or the speed of the gases is too great for them to be affected by the high temperature. Even cold air or gases are hard to control in comparatively small areas, but in a combustion chamber where very high and low temperatures are constantly moving in a great turmoil from one location to the next, a flame control has heretofore been only partly possible. This also is influenced by atmospheric conditions.

The results in oil burner efficiency of combustion heretofore obtained have accordingly been unsatisfactory. A great percentage of oil and oil gases escape unburned to the flue, in spite of an over supply of air or steam forced into the combustion chambers. The chambers therefore had to be of very large size, enlarging the area of the walls, which with the inefficiently large air supply further lowered the temperature of the fire gases. The partly burned or scorched oil changed into smoke, hot air intermingled with soot, which easily adhered to the steam producing elements of the boiler. On account of its great porosity, it acted as heat insulation which reduced the heat transfer from the combustion gases to the water to be evaporated or steam to be brought up to a higher temperature.

An object of the present invention is to so control incoming air and the gas mixture within an oil or pulverized coal combustion chamber, that such whirl or turmoil may be prevented, and result in more efficient combustion and increased heat for a given consumption of fuel. In accordance with my present invention, a de-

vice of a screen type, with relatively a large surface area, is positioned within the combustion chamber in such a manner as to extend throughout the width of the combustion chamber. The screen may comprise, for example heat resisting steel tubes or pipes, placed close enough to absorb and deflect the heat from the oil burners, and a row of links supported by the pipes. The tubes are arranged in substantially uniform spacing according to their weight and heat capacity. They are heated up to a maximum temperature of about 1000° F. so that no deformation may occur. The screen is continuously moved through the chamber, so that its parts travel through high temperature zones of the chamber.

The moving screen is preferably endless. It may be run either vertically or at almost any angle. When run at an acute angle upwardly, it depresses the fire gases downwardly, counteracting the tendency of the flames to shoot upwardly. The angle of inclination or positioning of the screen, relatively to particular zones of the combustion chamber, and in relation also to the location of the heater or boiler pipes, may be selected according to the conditions encountered. The screen is preferably moved twice across the path of the gases. A resistance is produced by the screen according to its dimensions and the spacing of its tubes and links. This equalizes the air pressure on the upward or downward moving sections of the screen. Gases and incoming air are thereupon thoroughly mixed twice, and brought up to a temperature where all the oil is completely gasified. The screen may be made to move four times across the gases, or two separate screens can be employed.

The screen tubes are preferably carried by linked chains which are run in depressions or channels in the furnace walls, so that the high temperatures do not affect them. The screen is of sufficient length so that the tubes and links will not be heated to too high a temperature and will run to some extent either overhead or underneath the combustion chamber where they may be cooled off sufficiently. This will preheat the air sufficiently for entry directly into the combustion chamber. The chain drive should preferably be so located that it may be readily serviced, and the tubes and links replaced when necessary.

With the above indicated features, objects and advantages in view, as well as others which will hereinafter appear, the invention resides in certain novel constructions and arrangements of

parts, the essential features of which are herein fully described and illustrated in the accompanying drawings, in which:

Fig. 1 is a longitudinal cross-sectional view through an oil burner furnace containing features of the present invention.

Fig. 2 is a cross-sectional view taken along the line 2—2 of the furnace of Fig. 1.

Fig. 3 is an enlarged exploded view of elements of the screen.

Fig. 4 is an enlarged view of chain elements for the screen.

Figs. 5 and 6 are fragmentary views of modified forms of drive wheel and chain arrangements for the screen.

Fig. 7 is a horizontal section, partly in elevation, through a furnace embodying a modification of invention.

Fig. 8 is a section taken along the line 8—8 of Fig. 7.

Fig. 9 is a fragmentary plan view of a modified form for the screen elements.

Fig. 10 is an end view of the screen of Fig. 9, as seen from the line 10—10.

Fig. 11 is a fragmentary view of a suspension link of a screen.

Fig. 12 is a horizontal cross-sectional view taken on the line 12—12 of Fig. 11.

The furnace of Figs. 1 and 2 comprises front wall 10, back wall 11, supporting inclined water or steam pipes 13 of standard construction, and side walls 14, 15. These walls form the combustion chamber 16 for the furnace above a bottom partition 17. Below partition 17 is lower chamber 21 formed by side walls 22, 22 front wall 23, back wall 24, and base 27. The lower chamber 21 communicates with combustion chamber 16 through apertures 25 and an opening or throat 26 in partition 17.

A blower 30 is installed in wall 23. Air is urged through chamber 21 by blower 30, by cooling purposes to be described. Wall 23 also has therein air inlet apertures 31. A nozzle 33 of an oil burner unit 34 is mounted in furnace front wall 10 to produce the usual oil spray 32. A pulverized coal unit or similar burner may be used. Air openings 35 of usual construction are shown in burner unit 34.

A cover or door 36 extends from the top of extended lower wall 23, affording access to the drive elements for the screen drive chain assembly 37. The drive elements comprise an electric motor 38 having a pinion 39 meshing with a gear 41. A pinion 42 driven by gear 41 meshes with sprocket drive gear 43 mounted on shaft 44. The teeth of sprocket gear 43 are in driving relationship with chain assembly 37. Chain 37 travels over idler sprocket gears 45, 45, upper idler sprocket gears 46, 46 and 47, 47 and rearward lower idler sprocket gears 49, 49. Gear sets 45 and 49 are mounted on shafts 52; and gear sets 46 and 47 on stub shafts 53 extending from supports 54 secured on walls of the furnace.

Screen drive chain 37 travels through opening 26 in partition 17, and along and in opposed channels 55, 55 in the side walls 14 and 15. The travelling heat equalizing screen comprises spaced cross tubes 56. Tubes 56, as shown in detail in Fig. 3, are integrally mounted with the chain assembly 37 through stud link-members 57, and studs 58 seated on segments 59 of tubes 56. A removable segment 60 of each tube 56 fits over the associated stud 58. Clamping plates 63, 64, having apertures 65 for bolts of usual construction, complete the assembly. The construction

at the opposite ends of the tubes 56 is similar. Associated with each stud link member 57 (see Fig. 4) is a chain link 66, and other parts such as pins or rivets 67, further connecting link members such as 68, 69 to form a sprocket or roller chain driven screen assembly.

Suspended from tubes 56 are spaced heat absorbing and delivering plates 73. Plates 73 are held against lateral displacement by pins 74. Members 56 and 73 of the screen absorb excessive heat from parts of the chamber 16, serve to equalize the combustion of the oil. The screen also delivers the heat to incoming air in the chamber 21, preheating said air for delivery into the combustion chamber 16. The horizontal and vertical spacing of the members 56 and 73 should be such that the refractory heat capacity of the screen will be sufficient, and close enough to vaporize even the smallest oil particles passing through the screen 37. The weight and surface area will determine the dimensions of the members, and the resistance or slowing down of the flow speed of the fire gases. Part of a standard boiler 13 is shown above the moving screen. Another section could well be located behind, or anywhere in the path of the fire gases.

The operation of the screen, in accordance with the invention is as follows. The screen is set in motion first, before the oil burner is operated. The oil and gas supply is preferably restricted in the beginning until the refractory mass of the screen is near its maximum degree of heat required to attain the complete gasification of the oil and heat transfer. With the increasing oil supply the volume of air is also increased, cooling down the returning screen members to protect them from overheating. This cooling down does not mean a loss of energy as the air is brought to a higher temperature and also assists a more rapid gasification. The screen should be inspected at regular intervals and worn or burned out parts replaced, depending on the weight of the equipment, length of service, and heat requirement.

A large amount of the fresh air supply enters through openings 31 and flows through chamber 21 and slots 25 into combustion chamber 16. While the screen is in passage 21 the cooler air absorbs some of its heat and lowers its temperature to such a degree that overheating during its travel through the combustion chamber 16 cannot take place. The weight of the refractory parts of the screen, length of travel through chamber 16, the volume of fresh air, and the speed of travel, are so balanced that the temperature of the metal parts of the screen remains as nearly constant as possible.

It is sometimes advantageous to bring the moving screen into proximity with the burner 33 so the oil spray comes into direct contact with more closely spaced and heavier members 56, 73 of the screen. The temperature of the moving screen should be considerably higher, therefore, to make the gasification almost instantaneous and complete, so that the air supply could be reduced to almost its theoretical minimum.

A modified suspensory element 173, similar to member 73, is shown in detail in Figs. 11 and 12. Element 173 has a lug 75, and is adapted for relative movable positioning on its tube 56. Element 173 is streamline in section as shown, having a blunt leading edge and a narrow trailing edge 76, to reduce resistance to the passage of air or gas about it. A further modified form for

member 73 is shown in Fig. 9 comprising a disk 273.

The structural arrangement shown in Fig. 5 may be used in combustion chambers of limited space. Top sprocket gears 46', 47' are like gears 46, 47 of Figs. 1 and 2, although in this case there is also a gear 78 to bring portions of screen chain 37 into closer relationship as shown. The sprocket gears 46', 47' shown in Fig. 6 afford different inclinations for the screen chain 37 than in Fig. 1.

In Figs. 7 and 8 another embodiment of the invention is shown. In this case a screen chain 37' travels horizontally, drive pinion 42' and gear 43' being arranged for this purpose. The sectional view Fig. 7 is taken through the boundary wall structure 11' of a chamber 16', and in said structure or wall is a horizontal channel 55'. The arrangement of Figs. 7 and 8 dispenses with connecting tubes, such as 56 of Figs. 1 and 2. On chain 37', are fastened horizontally spaced members 73'. Members 73' are on alternate link assemblies, and gears 45', 59' are arranged to carry the moving chain 37'. For small households, an installation of a corrugated disk or spider would have a similar effect as the moving screen. The screen in such case would comprise, for instance, heat resisting steel rods, tubes, or pipes which are placed close enough to absorb and reflect the heat from the oil burners and rows of vertical links, supported by the pipes and spaced apart equal distances according to their weight and heat absorption capacity to be heated up to a maximum temperature of about 1000 degrees to 1200 degrees Fahrenheit, so that no deformation may occur.

Although I have shown preferred arrangements for carrying out my invention, it is to be understood that modifications may be made therein that fall within the scope and principles thereof, as defined in the following claims.

What I claim is:

1. A heating apparatus having walls providing a combustion chamber, means for introducing fuel into said combustion chamber, a second chamber adjacent said combustion chamber having at least one opening communicating therewith, means for introducing air through said second chamber into said combustion chamber to burn the fuel therein and form combustion gases, rotary elements disposed in each of said chambers, a continuous flexible screen device mounted on said elements and arranged to pass through different temperature zones of said combustion chamber across the path of the combustion gases therein to equalize the heat distribution in said combustion chamber, and through said second chamber to heat the air therein, and means for revolving said elements and moving said device.

2. A heating apparatus having walls providing combustion and base chambers with an interposed communicating opening, the walls of the combustion chamber having therein opposed channels leading to the opening, means for introducing fuel into said combustion chamber, air supply means for said base chamber for introducing air into said combustion chamber to burn the fuel therein and form combustion gases, a heat transfer screen with one portion in the base chamber and another portion in the combustion chamber and disposed in the path of the combustion gases therein, said screen having a medial portion disposed in the opening, the edges of said screen being carried in said channels, and means for

moving said screen through said chambers to equalize the heat distribution in said combustion chamber and to heat the air in said base chamber.

3. A heating apparatus having walls providing an upper combustion chamber and a base chamber with at least one interposed communicating opening, means for introducing fuel into said combustion chamber, air supply means for said base chamber for introducing air into said combustion chamber to burn the fuel therein and form combustion gases, pairs of opposed rotary elements disposed in the upper chamber, pairs of opposed rotary elements in the lower chamber, pairs of opposed rotary elements at said opening, a heat transfer screen extending across the path of combustion gases in said combustion chamber and having side endless chains disposed on said elements, transverse rigid members connecting links of said chains, and spaced heat transfer suspensory elements carried by said transverse members.

4. An apparatus according to claim 3, in which the transverse members are hollow tubes.

5. An apparatus according to claim 3, in which said suspensory elements are of streamline cross-section.

6. A heating apparatus having walls providing an upper combustion chamber and a juxtaposed base chamber, said chambers having a transverse throat therebetween, a fuel injection nozzle in said combustion chamber, air supply means for said base chamber to introduce air into said combustion chamber to burn the fuel therein and form combustion gases, rotary sprocket gears within the upper chamber carried by the side walls thereof, rotary sprocket gears mounted in said base chamber, a pair of opposed endless sprocket chains carried by said gears, portions 40 of said chains being closer together at said throat, transverse rigid members connecting corresponding links of said sprocket chains, spaced suspensory elements on said rigid members to form a heat transfer screen disposed in the path of combustion gases in said combustion chamber and in the path of the air in said base chamber, and means for driving said screen through said chambers.

7. A heating apparatus having walls providing an upper combustion chamber and a juxtaposed base chamber with at least one interposed communicating opening, means for introducing fuel into said combustion chamber, air supply means for said base chamber for introducing air into said combustion chamber to burn the fuel therein and form combustion gases, pairs of opposed sprocket gears disposed in said upper chamber, pairs of opposed sprocket gears in said lower chamber, pairs of opposed sprocket gears at said opening, and a heat transfer screen extending across the path of combustion gases in said combustion chamber and comprising opposed endless side sprocket chains engaged with said gears, transverse tubes having their respective opposite ends connected to links of said chain, and spaced heat transfer members projecting from said tubes.

8. A heating apparatus including a combustion chamber and a base chamber having openings communicating with said combustion chamber, means for introducing fuel into said combustion chamber, means for introducing air into said base chamber to burn the fuel in said combustion chamber and form combustion gases therein, an endless heat transfer screen extending at least

once across said combustion chamber, in the path of the combustion gases therein, and through said base chamber and means for moving said screen through and between said chambers to equalize the heat distribution in said combustion chamber and heat the air entering said base chamber.

9. A heating apparatus having walls providing a combustion chamber and a base chamber with at least one interposed communicating opening, a fuel injection member in said combustion chamber, air supply means for said base chamber to introduce air into said combustion chamber to

burn the fuel therein and form combustion gases therein, a flexible movable heat transfer device having a portion opposite said member and disposed in the path of the combustion gases, another portion of said device extending in said base chamber to transfer heat to the air from said supply means, and a portion passing through said opening, and means for moving said device through said chambers and opening to equalize the heat distribution in said combustion chamber and heat the air in said base chamber.

MORITZ GAERTNER.
